UNITED STATES PATENT OFFICE.

HENRY FORD, OF DEARBORN, MICHIGAN.

EXPLOSIVE ENGINE.

Application filed August 2, 1920. Serial No. 400,638.

This invention relates to improvements in internal combustion motors.

A primary object of the present invention is the production of a motor of this type which is balanced mechanically and explosively to produce a structure which is easy running and in which the torque application closely approaches uniformity.

Another object is to provide a motor of compact formation, readily assembled and of durable construction.

Another object is the production of a motor of this type in which the weight factor when based on horse power production, is low.

Another object is the provision of a compact motor of this type operating under air-cooled principles, while maintaining the motor structure within comparatively small dimensions.

Further objects are the provision of special forms and constructions of various parts employed, the provision of novel arrangements for novel lubrication, novel arrangement of valve formations, manifolds, cylinders etc.

To these and other ends, therefore, the nature of which will be readily understood as the invention is hereinafter disclosed, said invention consists in the improved constructions and combinations of parts, hereinafter more fully described and illustrated in the accompanying drawings and more particularly pointed out in the appended claims.

In the accompanying drawings, in which similar reference characters indicate similar parts in each of the views,—

Figure 1 is a vertical sectional view taken on the line 1—1 of Fig. 4;

Fig. 2 is a view partly in section and partly in elevation, taken on the line 2—2 of Fig. 1;

Fig. 3 is a view on an enlarged scale of parts shown in Fig. 1, the view showing parts in section and parts in elevation;

Fig. 4 is a sectional view taken on the line 4—4 of Fig. 1;

Fig. 5 is a view in elevation looking at one end of the motor, parts being broken away to permit showing of the structure on a larger scale;

Fig. 6 is a detail sectional view taken through one of the manifold structures, and illustrating the manner in which the inlet and exhaust is controlled with respect to a plurality of cylinders;

Fig. 7 is a sectional view taken on the line 7—7 of Fig. 6;

Fig. 8 is a view of the structure of Fig. 7, the view being in end elevation and looking toward the right in Fig. 7;

Fig. 9 is a diagrammatic view illustrating the relative arrangement of cylinders and cranks to illustrate the operative relation between the various cylinders.

This invention pertains to motors of the four-cycle type, employing the general arrangement of the Otto cycle wherein the operating cycle of a cylinder is completed during two revolutions of the crank shaft, the cycle being made up of the four strokes of the piston operating within the cylinder.

In the embodiment of the invention shown, eight cylinders are employed arranged in two circular series of four each, the cylinders having an angular spacing of ninety degrees, the cylinders of the two series being alined in the direction of length of the crank shaft. In other words, the cylinders of a series are symmetrically disposed relative to and around the axis of the crank shaft, the second series being located alongside of the first series, so that a plane which would extend through the axis of alternate cylinders of the series—and through the axis of the crank shaft—would also extend through the corresponding cylinders of the second series, a cylinder from one series and its corresponding cylinder of the other series forming a pair of cylinders which are alined in the direction of length of the crank shaft.

The cylinders of a series each have their axes inclined to the vertical or horizontal, the arrangement being such that a cylinder practically has its axis extending at an angle of approximately forty-five degrees from the vertical or the horizontal, thus locating two cylinders of a series above and two below a horizontal plane extending through the crank shaft axis, or two cylinders on each side of a vertical plane extending through such axis, the two series producing the combined effect of having four cylinders above and four below a horizontal plane extending through the axis of the crank shaft, or four cylinders on each side of a vertical plane extending through such axis.

The crank shaft is formed with two cranks extending at one hundred and eighty degrees from each other, one crank operating with one series of cylinders, the other operating with the second series.

The arrangement is such that an explosion takes place at each ninety degrees of travel of the crank shaft, the power stroke of the piston of the cylinder being fired, however, continuing through a distance of travel of one hundred and eighty degrees of the crank shaft, the result being that there is a uniform overlapping of power strokes of successively fired cylinders, thus producing a more uniform torque effect and making possible the reduction in size of cylinders and pistons in the production of a motor of given horse power.

The motor is of the air cooled type, the cylinder formations carrying heat dissipating structures, and the crank shaft carrying one or more rotatable fan structures which are adapted to create a circulation of air about the heat dissipating formations.

The inlet supply and the exhaust gas discharge problem is met by employing manifolds at opposite sides of the motor with each manifold arranged to cooperate with the four cylinders which are located on a side, each manifold preferably having a formation such as to provide for fuel inlet into a chamber which has its walls located within the flow path of the exhaust gases, the arrangement providing for a common inlet and a common exhaust for each side of the motor located at one side of a vertical plane which extends longitudinally of and through the axis of the crank shaft. The manifold is located intermediate the upper and lower pairs of cylinders which it serves, thus making it possible to provide for substantially uniform length of connections leading from each cylinder to the manifold, and, since the number of cylinders in the direction of length of the manifold is but two, it will be readily understood that there is produced a more or less uniform action within the manifold due to the particular arrangement and to the fact that the order of igniting the charges of the respective cylinders is such that there is almost continuous intake and exhaust activity within the manifold throughout the cycles represented by two revolutions of the crank shaft. This latter will be readily understood by referring to Fig. 9 of the drawings in which is shown a diagrammatic view of the two series of cylinders with their respective piston and crank shaft connections and the general relation of cylinders heretofore pointed out. For instance, the upper portion of the figure represents one series, the lower portion representing the other series, the vertical plane which extends through the crank shaft being indicated by the dotted line —m—, it being understood that cylinders 1 and 5 are arranged side by side, while the similarly positioned remaining cylinders of the two parts of the figure are also arranged side by side.

The firing order of the cylinders is also indicated, the positions of the pistons as shown in this view however, being such as to start this firing order with cylinder 5, cylinders 1 and 2 completing the cycle by following cylinder 6.

As will be understood from the showing of this figure, travel of the crank shaft in the direction shown by the arrows in each portion, will produce the actions indicated in the drawings. For instance, cylinder 5 begins its power or ignition stroke, cylinder 1 which is located alongside of it, beginning the exhaust stroke of the piston; cylinder 7 is beginning the compression stroke, while cylinder 3, alongside of cylinder 7, is beginning the intake stroke, the crank shaft in this particular position, having its two cranks at points where the connecting rod for the pistons of these cylinders have just passed the dead center. As will be understood, these four strokes constitute a complete cycle, and each stroke is only completed when each of the cranks has reached a position one hundred and eighty degrees in advance of the position shown, movement of a crank from one position to the other in the direction indicated by the arrows, causing the pistons of these cylinders to be moved through the positions indicated with respect to the remaining cylinders, these latter having their pistons at approximately a mid-way position in the length of the particular stroke indicated.

The remaining cylinders, in the particular position shown are at the intermediate stroke positions. For instance, cylinder 2 is at the intermediate position of the power or ignition stroke, this cylinder being the preceding one in the order of firing; cylinder 6, which is positioned alongside of cylinder 2, is at the intermediate position of the exhaust stroke; cylinder 4, which is the succeeding cylinder to have its charge ignited is at the intermediate position of the compression stroke, and the similarly positioned cylinder 8 is at the intermediate position of the intake stroke.

When the crank shaft has advanced a distance of ninety degrees, the piston positions will have shifted so as to have the connecting rods of cylinders 2, 4, 6 and 8 in positions passing the dead center, the connecting rods of the remaining cylinders being canted. As a result, cylinder 4 is in position to begin its power stroke, cylinder 5 having reached the intermediate point of the power stroke, cylinder 7 having reached the intermediate position of the compression stroke, the completion of this stroke by the succeeding travel of the crank shaft placing this cylinder in condition for ignition; cylinder 2 has reached the end of its power stroke and begins its exhaust stroke, cylinder 1 is at the intermediate position of the exhaust

stroke, cylinder 6 has completed the exhaust stroke and is beginning the intake, cylinder 3 has reached the intermediate point of its intake stroke and cylinder 8 has reached the 5 end of its intake stroke.

A further travel of the crank shaft reverses the positions of the cranks shown in the two parts of the view, cylinder 7 being ready for ignition to provide the power 10 stroke, cylinder 5 having completed the power stroke and begins the exhaust stroke, cylinder 3 has completed its intake stroke and begins the compression stroke, while cylinder 1 has completed the exhaust stroke 15 and begins the intake, the remaining cylinders being at intermediate points.

This third position—which represents a travel of one hundred and eighty degrees of the crank shaft—has completed one stroke 20 in each of the odd numbered cylinders, but during its travel, cylinder 4 has added its power stroke at the ninety degree point in the travel of the crank shaft, so that during the period which represents a complete 25 stroke of the piston of a cylinder in which the piston is undergoing the power stroke, another piston also begins its power stroke when the crank shaft has advanced the ninety degrees angular distance. As a result, 30 there is an overlapping of power stroke effect throughout the period represented by two revolutions of the crank shaft, during which period the pistons of each of the cylinders has had a single power stroke of 35 the usual Otto type. Obviously, there is the same overlapping in connection with each of the other strokes of the Otto cycle.

By continuing the crank shaft travel through the successive angular distances of 40 ninety degrees which represent the periods of when a power stroke is begun, certain characteristics will be found which will not only provide for what may be termed an explosive balance, but will also indicate the 45 general activity of each of the manifolds, it being found, that while there are but four power strokes given by the cylinders connected to a single manifold, these power strokes extend through time intervals of 50 sufficient length to include a second power stroke, and since the remaining strokes of the Otto cycle type are of similar characteristic, there is presented a substantially constant intake and exhaust activity within the 55 manifold when the firing order disclosed is employed, one period (corresponding to the time-length required in crank shaft travel of ninety degrees) in the complete cycle of two crank shaft revolutions being free from 60 direct exhaust action from the cylinders connected to a manifold, and a similar period free from intake action. This is due to the fact that in the firing order cylinders 5 and 4 (having a common manifold connection) are in direct succession in their order, 65

as are cylinders 3 and 6 connected to the other manifold.

Another feature in connection with the arrangement shown, is that the distribution of explosions in the several cylinders, practically provides for two series, one above and the other below a horizontal plane extending through the axis of the crank shaft. This will be understood by noting that in the succession shown by the firing order, cylinders 4, 7, 8 and 3—all below such plane—follow each other in this order, while cylinders 6, 1, 2 and 5—all above such plane—also follow each other in this order, the explosion of a series, however, shifting backward and forward from one side to the other of a vertical plane through the crank shaft axis, so that alternate explosions take place on the same side of the vertical plane. As a result, there is an alternation of series 75 above and below the horizontal plane, while there is an alternation of cylinders relative to a vertical plane in each series, the variation being provided when the change is made from one series to the other, at which 80 time the shift is from the last cylinder of a series to the first cylinder of the other series, with both of said cylinders at the same side of the vertical plane; for instance, the shift 85 from cylinder 5 to cylinder 4 is from the upper to the lower side of the horizontal plane, while the shift of cylinder 3 to cylinder 6 is from the lower side to the upper side of such plane. This general arrangement and distribution of the explosion tends 90 to set up a balancing effect with respect to the explosions, providing what may be termed an explosive balance to the motor.

Referring more particularly to the structure disclosed in the drawings, 20 designates a casing, shown as formed of an upper section 20^a and a lower section 20^b, the division line being approximately on a horizontal plane extending through the axis of the crank shaft. The sections thereof represent configurations such as will provide for proper mounting of the elements presently described and to produce what may be termed a crank shaft chamber within which various structural elements enter and perform their functions. The sections are complementally formed to provide for a pair of crank shaft ball bearing structures 21 at opposite ends of the casing, these bearing structures being adapted to support end portions of the crank shaft.

The crank shaft, indicated generally at 22 is preferably of composite form, being made up of two members 23 and a cheek member 24. As shown more particularly in Fig. 2, each member 23 is provided with a crank arm 23^a from which extends a crank pin 23^b, the inner end of the pin being of a suitable spline formation adapted to cooperate with a complementary formation car-

ried by the cheek member 24, the latter having its axis alined with the axis of the crank shaft, the two crank pin structures being secured at opposite ends of the cheek member in suitable manner, the members 23 and cheek member 24, when thus assembled, producing a two crank crank shaft capable of being disassembled when required by removal of the securing means for retaining the cheek member in position. As will be seen, the cheek member is located at the inner ends of each of the crank pins, the latter having a length sufficient to not only engage the cheek member but to provide for an intermediate portion to which the connecting rods of the cylinders are operatively connected as presently described.

Members 23^a also preferably carry a suitable balancing weight 23^c, this being shown as alined with the crank arm 23^a of a crank shaft member.

The outer ends of members 23 are adapted to carry the hubs 25^a of fly wheels 25, the particular formation of such wheels shown being such as to provide blades 25^b to produce a construction operating on the general principles of a rotatable fan. It will be understood, of course, that the fly wheel construction need not include such blades, but since the motor is designed more particularly as an air-cooled motor, the presence of air circulating means of this type and at such locations is of special advantage. And it will be understood that the hubs 25^a may and do preferably carry formations capable of connecting the motor to a suitable shaft which is adapted to be driven thereby, Fig. 2 showing, at the right, a portion of a socket formation, which will permit of the mounting of a shaft or a shaft section, such for instance, as may be employed in connection with motor vehicle service.

26 designates a cylinder shown as secured within the casing with its axis extending radially to the crank shaft axis. In the particular embodiment of the invention shown, eight of these cylinders are employed, these cylinders having their axes extending at angles of substantially forty-five degrees from vertical and horizontal planes extending through the crank shaft axis, the cylinders being arranged in two series of four cylinders each, each series having the axes of its cylinders extending on a single vertical plane which intersects the crank shaft axis, at substantially right angles; the series are arranged side by side, as shown in Fig. 2, the vertical plane on which the cylinder axes of a series extends passing through the crank pin at a point intermediate the crank arm and the cheek member.

In the particular embodiment shown, the cylinders 26 are shown as made independent

of the casing, the latter having properly positioned openings with inwardly extending annular portions 20° through which the cylinders extend, a suitable seat formation being provided on which an annular flange 26^a is supported, the cylinder being held in place by a suitable threaded element 27 which overlies flanges 26^a and is threaded to the casing.

By this general arrangement, it is possible to produce the casing of a comparatively light metal such for instance as aluminum, while the cylinders are formed of a suitable grade of iron or steel. The invention, however, is not limited to this specific arrangement, since it is contemplated to divide the casing into either half or quadrant sections, and thus make possible the production of the cylinders of a half section or quadrant and the casing as a unitary structure.

As shown each cylinder is provided with external ribs or fins 26^b designed for heat dissipating purposes, and these fins are shown as also located at the outer ends of the cylinders, such outer ends having a more or less special configuration designed to aid in enhancing the operation of the motor.

This configuration of the head portion of the cylinder is shown as of integral structure with the body of the cylinder, the head portion being indicated at 28, said portion having a lateral extension 28^a to provide an enlarged portion or chamber into which the connections from the manifold are designed to deliver a charge, and from which these connections deliver the exhaust from the cylinder, the control to the connections being provided by inlet valves 29 and exhaust valves 30. As shown, the interior of head 28 extends in a curved line leading toward the chamber and designed to provide a gradual increasing width of space beyond the outer extreme of piston movement, this gradual increase being in a direction leading toward the chamber.

Lateral extension 28^a includes a portion having substantially the cross sectional configuration shown in Fig. 1, the latter indicating a section taken axially through the extensions of one series of cylinders. As will be seen, the extension carries a channel 28^b for the intake and a channel 28^c for the exhaust, these channels extending generally in a vertical direction with the inner ends curved to carry them to the plane of the outer ends of the cylinder body, such inner ends of the channel being provided with seats with which valves 29 and 30 cooperate. By extending channels 28^b and 28^c in a general vertical direction with the outer ends of these channels facing each other from an upper and a lower cylinder respectively, it is possible to mount a manifold structure intermediate such channel ends, making pos-

sible the use of a single manifold structure for the four cylinders located at one side of a vertical plane extending through the crank shaft axis.

5 Valves 29 and 30 have their axes substantially extending parallel to the cylinder axes, these valves being formed approximately as shown in Figs. 1 and 4, each valve stem extending through a sleeve 31 having a flange 31^a which is adapted to abut against a face of extension 28^a, sleeve 31 extending through an opening in said extension, and, if desired, into the channel 28^b or 28^c dependent upon which channel is to be controlled by the valve. The valve stem carries a suitable abutment 32 between which and flange 31^a is mounted a spring 33, said spring being designed to substantially retain the inner end of the stem in contact with a tappet member 34 which extends through an opening formed in the casing and which member has its inner end preferably enlarged as at 34^a to cooperate with a cam 35^a of a cam shaft 35 which extends 20 in a direction parallel to the direction of length of the crank shaft.

30 The valves for the upper pair of cylinders are located on the underside while those of the lower pair of cylinders are located on the upper side and the direction of length of the valves is such that the general axes of the valves for both pairs practically extend through the axis of cam shaft 35, said shaft being designed to control the operation of 35 the valves 29 and 30 of the two pairs of cylinders on one side of the vertical plane extending through the crank shaft axis.

As shown in Fig. 4, extensions 28^a of the upper pair of cylinders are offset with respect to the cylinder extensions of the lower pair of cylinders, the result being that while each cam shaft 35 carries all of the cams required for the valve operation, each valve is operated by its individual cam, the off-set relation providing a staggered formation as indicated in Fig. 4. As will be understood the cylinders on the opposite side of the vertical plane extending through the crank shaft axis are similarly mounted and have their valves operated by an independent shaft 35 as shown for instance, in Fig. 1.

Each spring 33 and the various parts which are located between the casing and extension 28^a are enclosed by a suitable casing 36.

65 Pistons 37 may be of any suitable formation, but it is preferred to employ a configuration such as indicated, for instance in Fig. 2 wherein the structure is generally hollow with the outer end closed and which is provided with an external configuration including a depressed portion 37^a in the zone of the usual pin formation which, in the present instance, is shown as a tubular pin 38, this pin being mounted inwardly

projecting portions 37^b, the inner ends of which are spaced apart sufficient to receive the outer tubular portion 39^a of a connecting rod 39, the drawings showing this portion as formed integral with the rod, but which, 70 could obviously, be formed as a separate element secured to the connecting rod. Depressed portion 37^a of the piston preferably carries a plurality of openings 37^c, and the piston itself also preferably carries a plurality of openings 37^d adjacent the piston rings, these various openings affording communication between the inside of the piston and the piston face which operates in contact with the cylinder. 80

85 Connecting rods 39 are shown as tubular, with the inner ends in the form of a shoe 39^b—shown as integral, but which may obviously be a secured structure—the shoe being extended laterally so as to project between a bushing 40, mounted on pin 23^b and a pair of annular collars 41 located on opposite sides of the rod, the shoe having a length in the direction of crank shaft travel greater than the diameter of the connecting rod, but less than the distance corresponding to an angular distance of ninety degrees of the bushing. The approximate length of shoe is shown more particularly in Fig. 1, the arrangement being such as to 90 permit the inner ends of the four connecting rods, the shoes of which are those mounted on a crank pin, to move relatively to each other as the pin travels in its orbit, the arrangement permitting proper compensation for the change in angularity of the connecting rod as the various piston strokes are produced. 95

100 By the general arrangement shown, it will be readily understood that repairs and replacements of the parts can be readily had by reason of the ability to disconnect the cheek member 24 from a crank pin. This can be done by first removing the upper section 20^a of the casing with the upper cylinders, thus exposing the crank shaft formation and the pistons attached thereto by the formation which secured the inner end of the rods to bushing 40. The crank shaft is raised a distance sufficient to permit lateral shifting of one of the members 23, after which that cap screw or other securing means for the cheek member mounted in the particular member 23 which carries the connecting rod structure which is being replaced or repaired, is removed, thus permitting the member 23 to be withdrawn from the bushing, leaving the connecting rod shoes still positioned on the bushing. 110 One of the collars 41 may then be removed, permitting the connecting rod to be shifted out of position without affecting the remaining rods, after which the substituted rod is placed in position, the collar replaced, thus 115 restoring the general connection between 120 125 130

the series of connecting rods and the bushing after which member 23 is replaced, the securing means restored, the crank shaft returned to its proper position and the upper section restored. This is made possible not only by reason of the fabricated form of connecting rod, but also by reason of the use of bushing 40 which retains the assembly of connecting rod shafts in their general arrangement even though member 23 be removed, so that in assembling or taking down the connecting rod structure there is no disturbance of the general arrangement, it being possible to assemble the four piston structures on the bushing in advance of the introduction of the crank pin into the bushing; and this same assembly remains, of course, when the crank pin is withdrawn to permit access to the collars 41.

20 The spark plug for ignition may be located at any suitable point, but it is preferred to locate it at the end of lateral extension 28^a, as indicated, for instance at 42. The several spark plugs pertaining to 25 the pairs of cylinders located at one side of the vertical plane extending through the crank shaft axis are controlled from a suitable timer, located at an end of the casing, the casing of said timer being indicated at 30 43 in Fig. 5, two such timing structures being preferably employed and located to have a movable element thereof carried by cam shaft 35, said cam shaft being driven from the crank shaft by suitable gears 44 35 meshing with a gear 45 mounted on the crank shaft.

One embodiment of a manifold adapted to be used in the present embodiment of the invention is shown in Figs. 6, 7, and 8 in 40 which a casting 46 (shown in Fig. 7) is provided with an exhaust chamber 47 and an intake chamber 48, the latter having a suitable passageway 48^a leading thereto and which is connected up with the carburetor structure or structures, the exhaust chamber having an outlet 47^a leading to a suitable point, such for instance as a muffler, not shown. As seen in Figs. 6, 7 and 8 the major portion of the walls of chamber 48 45 are exposed within chamber 47, so that the walls of the intake chamber are practically bathed with the exhaust gases, thus primarily heating the intake prior to the delivery of the charge to the cylinder.

55 Figure 6 shows the manner in which the manifold can be connected up to the lateral extensions 28^a, it being seen that intake channels 28^b are the intermediate channels, leading into chamber 48 by their connections 49, the exhaust channels 28^a being the outer channels and leading into chamber 47, similar connections 49 being provided.

As will be seen all of the intakes for the four cylinders are of substantially the same 60 length as are the exhaust connections, so

that there is a practical uniformity in action within the manifold, as hereinbefore more fully described.

Lubrication of the motor may be had in any desired manner, a preferred arrangement, however, being that disclosed in the drawing, wherein 50 indicates a tank for the lubricant, this tank being secured at the bottom of casing 20 between the two pairs of cylinders carried by section 20^b, the tank being of suitable configuration, that shown in the drawings being especially suitable for the purpose, this tank having a length sufficient to overlie a pair of openings 20^c located at the bottom of section 20^b practically in alignment with the axes of the different vertical series of cylinders, openings 20^c being designed to receive depending oil straining elements 51, these being shown as in the form of a mesh structure of suitable type and which extend into juxtaposition to the bottom of the tank, being designed to permit of the passage of oil from the bottom of the lower section of casing 20 into the tank, the straining element being closed at the bottom.

52 indicates a rotary pump carried at the lower end of a stand pipe structure 53, the latter extending at an inclination to the vertical from a point adjacent the bottom of tank 50 to a point adjacent one of the cam shafts 35, the pump being driven from the cam shaft 35 by a shaft 54 extending axially through the stand pipe 53, such shaft 35 and shaft 54 having a gear connection whereby the rotating element of the pump is driven in a direction to take up oil from the tank and deliver it to the stand pipe external of shaft 54, the stand pipe having a diameter sufficient to provide for the upward travel of oil delivered by the pump into a channel 55 carried by section 20^b, said channel leading to a pipe connection 56 which is carried upwardly and then inwardly from a side of the interior of the casing to a point above the crank shaft axis, the pipe having branches 56^b which lead laterally of the direction of length of the pipe to points located above the path of travel of the connecting rod shoes, as shown more particularly in Fig. 2, a shield 57 being provided between pipe 56 and the path of travel of the cheek member.

By this arrangement oil is delivered from the tank through branches 56^b and permitted to drip upon the connecting rod structure mounting at the inner ends of the connecting rods, thus lubricating the shoe mountings to permit of proper lubrication, and since the crank shaft is operating at a comparatively high speed, there will be a tendency for oil to be thrown outwardly by centrifugal action set up by motion of the crank shaft, this tending to carry lubricant into the connection at the outer ends of the 130

connecting rods and on to the cylinder walls, openings 37° of the piston permitting passage of any oil which might spatter, these general arrangements tending to maintain the cylinders properly lubricated.

As will be readily understood, the opposite sides of the motor are practically balanced relative to each other so far as structure is concerned, so that the motor is substantially balanced mechanically and therefore adapted to operate with a minimum amount of vibration. And as heretofore pointed out, the general arrangement and order of firing is such as to produce substantially a balanced condition explosively, the result being the production of a motor of compact form and capable of withstanding the severe conditions of use.

The arrangement is such as to permit of the use of cylinders of comparatively small diameter. For instance, the cylinders of one form of the motor have an internal diameter of two and one-half inches with the length of the piston stroke two and three-quarters inches. With these dimensions it is possible to produce a power value of from twenty-five to thirty horse power, with the weight of the motor approximately three pounds per horse power.

I have shown the preferred embodiment as employing two series of cylinders with each series having four individual cylinders, the pistons of which have their connecting rods connected to a single crank. This provides for the mechanical and explosive balancing of the motor. It will be obvious, however, that the number of cylinders in a series may be increased, or the number of series may be increased by increasing the length of the crank shaft and employing additional cranks through continuing the fabricated form of crank shaft.

While I have herein shown and described a preferred arrangement, it will be readily understood that changes and modifications therein may be found desirable or essential in meeting the various exigencies of use, and I desire to be understood as reserving the right to make any and all such changes or modifications as may be found desirable or essential, in so far as the same may fall within the spirit and scope of the invention as expressed in the accompanying claims when broadly construed.

Having thus described my invention, what I claim is:—

1. In an internal combustion motor of the Otto cycle type, a crank shaft, a plurality of cylinders symmetrically disposed with respect to said shaft, and pistons for the cylinders operatively connected with the crank shaft, said cylinders being arranged in more than a single circular series in the direction of length of the shaft with each series having the pistons of its cylinders

operatively connected to the same crank of the shaft with the connections of the pistons and crank shaft similar with each of the pistons of the series, each cylinder being inclined relative to planes extending horizontally and vertically through the crank shaft axis, the cylinders on one side of the vertical plane having the intake and exhaust service instrumentalities in common and independent of the similar instrumentalities of the cylinders on the other side of such plane, each intake and exhaust service instrumentality including a combined intake and exhaust manifold formation positioned between the cylinders served thereby.

2. In an internal combustion motor of the Otto cycle type, a crank shaft, a plurality of cylinders symmetrically disposed with respect to said shaft, and pistons for the cylinders operatively connected with the crank shaft, said cylinders being arranged in more than a single circular series in the direction of length of the shaft with each series having the pistons of its cylinders operatively connected to the same crank of the crank shaft with the connections of the pistons and crank shaft similar with each of the pistons of the series, each cylinder being inclined relative to planes extending horizontally and vertically through the crank shaft axis, the cylinders of each series having substantially the same inclination relative to such planes, the cylinders on one side of the vertical plane having the intake and exhaust service instrumentalities in common and independent of the similar instrumentalities of the cylinders on the other side of such plane, each intake and exhaust service instrumentality including a combined intake and exhaust manifold formation positioned between the cylinders served thereby.

3. In an internal combustion motor of the Otto cycle type, a crank shaft, a plurality of cylinders symmetrically disposed with respect to said shaft, and pistons for the cylinders operatively connected with the crank shaft, said cylinders being arranged in more than a single circular series in the direction of length of the shaft with each series having the pistons of its cylinders operatively connected to the same crank of the shaft with the connections of the pistons and crank shaft similar with each of the pistons of the series, each cylinder being inclined relative to planes extending horizontally and vertically through the crank shaft axis, each series consisting of four cylinders, the cylinders on one side of the vertical plane having the intake and exhaust service instrumentalities in common and independent of the similar instrumentalities of the cylinders on the other side of such plane, each intake and exhaust service in-

strumentality including a combined intake and exhaust manifold formation positioned between the cylinders served thereby.

4. In an internal combustion motor of the Otto cycle type, a crank shaft, a plurality of cylinders symmetrically disposed with respect to said shaft, and pistons for the cylinders operatively connected with the crank shaft, said cylinders being arranged in more than a single circular series in the direction of length of the shaft with each series having the pistons of its cylinders operatively connected to the same crank of the shaft with the connections of the pistons and crank shaft similar with each of the pistons of the series, each cylinder being inclined relative to planes extending horizontally and vertically through the crank shaft axis, each series consisting of four cylinders with a pair of cylinders located on each side of such horizontal plane, the cylinders on one side of the vertical plane having the intake and exhaust service instrumentalities in common and independent of the similar instrumentalities of the cylinders on the other side of such plane, each intake and exhaust service instrumentality including a combined intake and exhaust manifold formation positioned between the cylinders served thereby.

5. In an internal combustion motor of the Otto cycle type, a crank shaft, a plurality of cylinders symmetrically disposed with respect to said shaft, and pistons for the cylinders operatively connected with the crank shaft, said cylinders being arranged in more than a single circular series in the direction of length of the shaft with each series having the pistons of its cylinders operatively connected to the same crank of the shaft with the connections of the pistons and crank shaft similar with each of the pistons of the series, each cylinder being inclined relative to planes extending horizontally and vertically through the crank shaft axis, each series consisting of four cylinders, with a pair of cylinders located on each side of such vertical plane, the cylinders on one side of the vertical plane having the intake and exhaust service instrumentalities in common and independent of the similar instrumentalities of the cylinders on the other side of such plane, each intake and exhaust service instrumentality including a combined intake and exhaust manifold formation positioned between the cylinders served thereby.

6. In an internal combustion motor of the Otto cycle type, a crank shaft, a plurality of cylinders symmetrically disposed with respect to said shaft, and pistons for the cylinders operatively connected with the crank shaft, said cylinders being arranged in more than a single circular series in the direction of length of the shaft with each series having the pistons of its cylinders operatively

connected to the same crank of the shaft with the connections of the pistons and crank shaft similar with each of the pistons of the series, each cylinder being inclined relative to planes extending horizontally and vertically through the crank shaft axis; each series consisting of four cylinders, with each cylinder extending at an angle of approximately forty-five degrees to such horizontal and vertical planes, the cylinders on one side of the vertical plane having the intake and exhaust service instrumentalities in common and independent of the similar instrumentalities of the cylinders on the other side of such plane, each intake and exhaust service instrumentality including a combined intake and exhaust manifold formation positioned between the cylinders served thereby.

7. In an internal combustion motor of the Otto cycle type, a crank shaft, a plurality of cylinders symmetrically disposed with respect to said shaft, and pistons for the cylinders operatively connected with the crank shaft, said cylinders being arranged in more than a single circular series in the direction of length of the shaft with each series having the pistons of its cylinders operatively connected to the same crank of the shaft with the connections of the pistons and crank shaft similar with each of the pistons of the series, each cylinder being inclined relative to planes extending horizontally and vertically through the crank shaft axis, the cylinders of each series having substantially the same inclination relative to such planes, the cranks for the cylinders of adjacent series being spaced approximately one hundred and eighty degrees apart, the cylinders on one side of the vertical plane having the intake and exhaust service instrumentalities in common and independent of the similar instrumentalities of the cylinders on the other side of such plane, each intake and exhaust service instrumentality including a combined intake and exhaust manifold formation positioned between the cylinders served thereby.

8. In an internal combustion motor of the Otto cycle type, a casing, a crank shaft carried thereby, a plurality of cylinders carried by the casing with the cylinders arranged in longitudinal rows with the rows symmetrically disposed in inclined relation to each other and to horizontal and vertical planes extending through the crank shaft axis, the cylinders with pistons operatively connected to the same crank of the crank shaft forming a circular series with the cylinder axes extending on the same vertical plane, pistons for the respective cylinders and operatively connected to the crank shaft, inlet and exhaust valves for each cylinder with the valve axis positioned offset with relation to and extending substantially

parallel with the corresponding cylinder axes, a cam shaft within the casing for and individual to the valves of the cylinders on each side of such vertical plane, said shafts 5 being located on such horizontal plane, operating connections between the cam shaft and the valves, the cylinder arrangement being such as to provide a succession of circular series with the pistons of each series operatively connected with the same crank of the crank shaft.

9. A motor of the type of claim 8 characterized in that the heads of the several cylinders project laterally of the cylinder to 15 provide a chamber offset with relation to the cylinder and forming a passageway for fuel and combustion products, the valves being operative to control communication to and from said chamber, the head extensions 20 of the cylinders on each side of the vertical plane being on the inner side of the cylinder.

10. A motor of the type of claim 8 characterized in that the heads of the several cylinders project laterally of the cylinder to 25 provide a chamber offset with relation to the cylinder and forming a passageway for fuel and combustion products, the valves being operative to control communication to and from said chamber, the head extensions of 30 the cylinders on each side of the vertical plane being on the inner sides of the cylinders and extending in the direction of the horizontal plane through the crank shaft, the axes of the valve seats of such cylinders 35 intersecting a plane parallel to such vertical plane.

11. A motor of the type of claim 8 characterized in that the heads of the several cylinders project laterally of the cylinder to 40 provide a chamber offset with relation to the cylinder and forming a passageway for fuel and combustion products, the valves being operative to control communication to and from said chamber, the head extensions 45 of the cylinders on each side of the vertical plane being on the inner sides of the cylinders, the valve seat axes intersecting a plane parallel to such vertical plane, the passageways leading from the manifold structure 50 to said chambers extending in such parallel plane.

12. A motor of the type of claim 8 characterized in that the heads of the several cylinders project laterally of the cylinder to 55 provide a chamber offset with relation to the cylinder and forming passageways for fuel and combustion products, the valves being operative to control communication to and from said chamber, the head extensions of 60 the cylinders on each side of the vertical plane being on the inner sides of the cylinders, said extensions having openings to receive igniting structures, the axis of such openings extending transverse to the valve 65 axes of the extension.

13. In an internal combustion motor, a crank shaft, a plurality of cylinders arranged in a succession of circular series symmetrical to the crank shaft axis, pistons for the cylinders with the pistons of a series 70 operatively connected to the same crank of the crank shaft, each series having a pair of cylinders symmetrically disposed on each side of a vertical plane extending through the crank shaft axis with the cylinders of a 75 pair located on opposite sides of a horizontal plane extending through said axis, each cylinder of a pair having inlet and exhaust ports with the axis of each port intersecting a plane parallel to such vertical plane, a manifold having passageways extending on such parallel plane, and connections between the cylinder ports and the manifold passageways, said connections also extending on such plane. 80

14. A motor as in claim 13 characterized in that the manifold structure is positioned approximately midway between the ports of the pairs of cylinders. 85

15. In an internal combustion motor, a crank shaft, a plurality of cylinders arranged in a succession of circular series symmetrical to the crank shaft axis, pistons for the cylinders with the pistons of a series 90 operatively connected to the same crank of the crank shaft, each series having a pair of cylinders symmetrically disposed on each side of a vertical plane extending through the crank shaft axis with the cylinders of a 95 pair located on opposite sides of a horizontal plane extending through said axis, each cylinder of a pair having inlet and exhaust ports with the axis of each port intersecting a plane parallel to such vertical plane, a manifold having passageways extending on such parallel plane, and connections between the cylinder ports and the manifold passageways, said connections also extending on such plane, said connections being of substantially equal length. 100

16. A motor as in claim 13 characterized in that the manifold structure is positioned approximately midway between the port of the pairs of cylinders, and located on such 105 horizontal plane. 110

17. In an internal combustion motor, a crank shaft, a plurality of cylinders arranged in a succession of circular series symmetrical to the crank shaft axis, pistons for the cylinders with the pistons of a series 120 operatively connected to the same crank of the crank shaft, each series having a pair of cylinders symmetrically disposed on each side of a vertical plane extending through the crank shaft axis with the cylinders of a 125 pair located on opposite sides of a horizontal plane extending through said axis, each cylinder of a pair having inlet and exhaust ports with the axis of each port intersecting a plane parallel to such vertical 130

plane, a manifold having passageways extending on such parallel plane, and connections between the cylinder ports and the manifold passageways, said connections also 5 extending on such plane, said manifold having a formation to accommodate both intake and exhaust gases, the connections of intake and exhaust between a row of cylinders and the manifold being of substantially equal length.

18. In an internal combustion motor, a crank shaft, a plurality of cylinders arranged in a succession of circular series symmetrical to the crank shaft axis, pistons for 15 the cylinders with the pistons of a series operatively connected to the same crank of the crank shaft, each series having a pair of cylinders symmetrically disposed on each side of a vertical plane extending through 20 the crank shaft axis, with the cylinders of a pair located on opposite sides of a horizontal plane extending through said axis, each cylinder of a pair having inlet and exhaust ports with the axis of each port intersecting 25 a plane parallel to such vertical plane, a manifold having passageways extending on such parallel plane, and connections between the cylinder ports and the manifold passageways, said connections also extending 30 on such plane, said manifold having a formation to accommodate both intake and exhaust gases the connections of intake and exhaust between the manifold and the several cylinders being of substantially equal 35 length.

19. In an internal combustion motor, a casing having a bottom, a crank shaft supported by said casing, a plurality of cylinders arranged in a succession of circular 40 series symmetrically disposed to the crank shaft axis with the cylinders of the several series extending in alinement longitudinally of the crank shaft axis, the cylinders of a series being inclined to a vertical plane extending through the crank shaft axis, the pistons of a circular series being operatively connected to the same crank of the crank shaft, an oil reservoir carried by and depending from said casing below said bottom 45 and being symmetrically disposed relative to such plane, said reservoir having a cross-sectional configuration to produce a greater width at its bottom than at its top, and oil-distributing mechanism extending 50 into the reservoir, said mechanism including a pump active within the reservoir, the cross-sectional configuration of the reservoir permitting the portion of the mechanism within the reservoir to extend obliquely 55 therein in continuation of the distributing mechanism within the casing.

20. In an internal combustion motor, a casing having a bottom, a crank shaft supported by said casing, a plurality of cylinders arranged in a succession of circular 60

series symmetrically disposed to the crank shaft axis with the cylinders of the several series extending in alinement longitudinally of the crank shaft axis, the cylinders of a series being inclined to a vertical plane extending through the crank shaft axis, the pistons of a cylinder series being operatively connected to the same crank of the crank shaft, and an oiling system for the motor, said system including an oil reservoir depending from the casing below said bottom and in symmetrical relation to such plane, a pump structure mounted to operate in said reservoir, said structure having an axis extending in a direction inclined to the vertical and horizontal, and a conduit system leading from said pump and having oil discharge ports positioned to permit oiling of the crank mountings of the piston connecting rods.

21. In an internal combustion motor, a casing, a crank shaft supported by said casing, a plurality of cylinders arranged in a succession of circular series symmetrically disposed to the crank shaft axis with the cylinders of the several series extending in alinement, longitudinally of the crank shaft axis, the cylinders of a series being inclined to a vertical plane extending through the crank shaft axis, the pistons of a circular series being operatively connected to the same crank of the crank shaft, and an oiling system for the motor, said system including an oil reservoir depending from the casing in symmetrical relation to such plane, and a pump structure operative to deliver oil from the reservoir for delivering oil to the crank mountings of the piston connecting rods, said structure including a barrel formation having a length to project into said reservoir and to a point within the casing adjacent a horizontal plane extending through the crank-shaft axis, said barrel carrying a rotatable pumping element within the reservoir and an operating stem extending longitudinally of the barrel, said stem having a driven relation with a drive element within the casing, said barrel having a configuration to produce a channel therein external of the stem with the channel communicating with the pump at one end and with an oil-delivering conduit system at its opposite end.

22. In an internal combustion motor, a casing, a crank shaft supported by said casing, a plurality of cylinders arranged in a succession of circular series symmetrically disposed to the crank shaft axis with the cylinders of the several series extending in alinement, longitudinally of the crank shaft axis, the cylinders of a series being inclined to a vertical plane extending through the crank shaft axis, the pistons of a circular series being operatively connected to the same crank of the crank shaft, and an

oiling system for the motor, said system including an oil reservoir depending from the casing in symmetrical relation to such plane, and a pump structure operative to deliver oil from the reservoir for delivering oil to the crank mountings of the piston connecting rods, said structure including a barrel formation having a length to project into said reservoir and to a point within the casing adjacent a horizontal plane extending through the crank-shaft axis, said barrel carrying a rotatable pumping element within the reservoir and an operating stem extending longitudinally of the barrel, said stem having a driven relation with a drive element within the casing, said barrel having a configuration to produce a channel therein external of the stem with the channel communicating with the pump at one end and with an oil delivering conduit system at its opposite end, the axis of the barrel being inclined to and intersecting such vertical plane.

23. A motor of the type of claim 20 characterized in that the conduit system includes a pipe connection extending in a plane extending transversely of the crank shaft axis intermediate successive series of pistons, said connection having branches positioned to deliver oil to mountings adjacent such plane.

24. A motor of the type of claim 20 characterized in that the conduit system includes a pipe connection extending in a plane extending transversely of the crank shaft axis intermediate successive series of pistons, said connection having branches positioned to deliver oil to mountings adjacent such plane, the casing carrying a shield located in such plane intermediate such delivery points.

25. In an internal combustion motor, a casing, a crank shaft carried by the casing and having its axis extending in a horizon-

tal plane, a plurality of cylinders arranged in a succession of circular series symmetrically disposed to the crank shaft axis with the cylinders of successive series extending in alignment longitudinally of such axis, pistons for said cylinders with the pistons of a series operatively connected with the same crank of the crank shaft, said casing being formed sectional with a mating line of the sections extending in approximate correspondence with the horizontal plane extending through the crank shaft axis, said motor having a pair of cam shafts for the cylinders with the shafts located on the opposite sides of a vertical plane extending in the direction of length of the crank shaft axis, said cam shafts lying in the plane of the mating line and spaced equidistant from the crank shaft axis.

26. In internal combustion motors, a crank shaft, a plurality of cylinders symmetrically disposed with respect to said shaft, pistons for the cylinders and operatively connected to the crank shaft, said cylinders being in circular series and inclined relative to a vertical and a horizontal plane through the crank shaft axis with the cylinders equal in number on the opposite sides of such vertical plane to produce a group relation of the cylinders on a side with each group having a cylinder on each side of the horizontal plane, an individual cam shaft for the valves of each group, and a timer unit individual to each group operative in synchronism with the cam shaft of its group, the several timer units being located at opposite sides of the crank shaft axis and each symmetrically disposed relative to a horizontal plane extending through such axis and through said units.

In testimony whereof I affix my signature.
HENRY FORD.
